UNITED STATES PATENT OFFICE.

HORIS G. FRANCIS, OF DEXTER, MISSOURI.

PEA-HULLER.

SPECIFICATION forming part of Letters Patent No. 597,609, dated January 18, 1898.

Application filed June 9, 1897. Serial No. 640,022. (No model.)

To all whom it may concern:

Be it known that I, HORIS G. FRANCIS, a citizen of the United States, residing at Dexter, in the county of Stoddard and State of Missouri, have invented a new and useful 5 Pea-Huller, of which the following is a specification.

This invention relates to pea or bean hullers, its object being to improve the construction 10 of machines of this character whereby they will be rendered more efficient in operation.

With this and other objects in view the invention consists of the several details of construction and combinations of parts, as will 15 be hereinafter fully described, and particularly pointed out in the claims.

In the drawings, Figure 1 is a perspective view of a pea-huller made in accordance with my invention. Fig. 2 is a vertical longitudinal 20 section. Fig. 3 is a vertical transverse section. Fig. 4 is a rear end view.

Similar reference-numerals indicate similar parts in the several figures.

1 indicates the main casing of the machine, 25 which may be of any desired length and width and be supported upon wheels 2 in the ordinary manner.

3 indicates a casing projecting upwardly at the front end of the main casing and communicating therewith, and within this casing is secured the concave 4, and the cylinder 5 also works within this casing. The shaft 6 of the cylinder constitutes the main driving-shaft and is supported in suitable bearings on the 30 frame of the machine. This shaft projects at each end beyond the sides of the casing 1 and is provided at one end with a belt-pulley 7, from which a drive-belt 8 leads to a suitable source of power. (Not shown.) The cylinder 35 is provided with a series of round pins 9, which coöperate with similar pins 10 on the concave to hull the peas or beans. At the upper end of the concave are a series of knives 11, projecting inwardly toward the cylinder, and between which the pins on the cylinder are adapted to work. The object of providing 40 these knives is to cut the vines into short pieces as they are fed into the machine and thereby greatly facilitate the threshing out 45 of the peas or beans with the expenditure of 50

much less power than would be required if the vines were fed in full length.

12 indicates a vibrating screen which inclines upwardly from the front to the rear of the machine, and the perforations 13 of this 55 screen are of sufficient size to permit the peas or beans to pass freely through them. The screen is supported at each end upon rollers 14, which are journaled in suitable bearings in the frame of the machine, and the screen 60 is moved longitudinally to and fro on these rollers in a manner to be hereinafter described.

15 indicates an endless belt which is supported on rollers 16 and 17, the former being 65 at the front end of the machine and the latter at its rear end. The shaft 18 of the roller 16 is provided with a pulley 19 outside of the casing, and the shaft 6 is provided with a pulley 20 in alinement with the pulley 19, and a 70 belt 21 transmits movement from the pulley 20 to the pulley 19 and thereby drives the endless belt 15. The belt may be of canvas or any other suitable material and is of substantially the same width as the vibrating 75 screen 12. A series of cross-bars 22 are secured to the belt, and each bar is provided with a series of teeth 23, which are adapted to work in contact with the upper face of the screen 12 and are for the purpose of carrying 80 off vines and hulls to discharge them from the rear end of the machine and also to aid the peas or beans to pass through the perforations in the screen. The front end of the belt is directly below the concave, and the 85 vines, hulls, and peas are discharged from the concave onto the belt, which in turn transfers them to the screen and moves them up the incline until the peas are separated from the hulls and vines, which latter are 90 then discharged at the rear end of the machine.

24 indicates a shaft which is journaled in suitable bearings at the rear end of the machine and projects outwardly at one end beyond the casing, where it is provided with a pulley 25. The inner end of the shaft carries a crank-wheel 26, and a rod 27 connects the crank on the wheel to the vibrating screen 12. The shaft 18 is provided with a pulley 28, and 100

from this pulley a belt 29 leads to the pulley 25 and thereby transmits motion to the shaft 24 and crank-wheel 25, which results in giving the screen a reciprocating movement end-
wise on its supporting-rollers 14.

30 indicates a fan at the front end of the machine, the shaft 31 of which is journaled in suitable bearings in the casing 1. The shaft 31 projects at one end beyond the casing 10 and is provided with a pulley 32, which is in alinement with a pulley 33 on the shaft 6, and a belt 34 connects these two pulleys and thereby transmits motion from the drive-shaft 6 to the fan. This fan is so arranged as to drive a current of air through the peas, hulls, and vines, &c., as they fall from the concave onto the belt, and thereby carries the lighter rubbish and dust out through the rear end of the machine. The shaft 6 is provided with a suitable fly-wheel 35 in the usual manner.

The screen 12 is secured to the upper face of the side rails 36, and an imperforate plate 37 is secured to the lower surfaces of the said rails, to be substantially parallel with the screen, and the peas or beans which pass through the perforations in the screen fall on the plate 37 and roll down into the trough 38, which extends transversely of the machine, 30 and from this trough they may be discharged into any suitable receptacle. A suitable hopper 39 may be arranged over the cylinder and concave to receive the vines, from which they may be gradually fed into the concave to be threshed.

In operation the vines as they are received from the field will be fed into the concave and be forced between the knives 11 by the pins 9 on the cylinder and cut into short 40 lengths, after which the pins on the concave and cylinder will coöperate to thresh out the peas, and the peas, hulls, and short vines will be discharged from the concave onto the endless belt 15 and then carried up the vibrat- 45 ing screen 12, and during their movement up the screen the peas will pass through the perforations and the hulls and vines will be discharged out at the rear end of the machine.

It will be understood that changes in the 50 form, proportion, and the minor details of construction may be resorted to without departing from the spirit or sacrificing any of the advantages of this invention.

Having thus described the invention, what 55 I claim is—

1. In a pea-huller, the combination of a mechanism for cutting up the vines and threshing out the peas, an upwardly and rearwardly inclined screen having its front end below the threshing mechanism, means 60 for imparting an endwise-reciprocating movement to the screen, an endless belt mounted to travel parallel with and above the screen with its upper portion moving toward the front of the machine and adapted to receive 65 the vines, hulls and peas, and pins projecting from the belt to work over the screen, substantially as and for the purpose specified.

2. In a pea-huller, the combination with a screen supported in the frame and inclined upwardly from the front to the rear end of the machine, means to reciprocate said screen endwise, an endless belt mounted to travel parallel to the screen with its upper side moving toward the front of the machine, pins projecting from the belt to work over the surface of the screen, a concave and cylinder adapted to thresh out the peas and discharge the pea vines and hulls onto the upper side of the endless belt, and a fan to force a current of 80 air through the vines, peas, &c., as they fall from the concave to the belt, substantially as described.

3. In a pea-huller, the combination of a screen supported within the frame and inclined upwardly from the front to the rear end of the machine, means to reciprocate said screen endwise, an endless belt mounted to travel parallel to the screen with its upper side moving toward the front of the machine, pins projecting from the belt to work over the screen, an inclined plate rigidly connected to and arranged below the screen to move with it and receive the peas therefrom, a concave and cylinder adapted to cut the vines 95 into short lengths, thresh out the peas and discharge the peas, vines, &c. onto the upper side of the endless belt, and a fan mounted to revolve in the front of the machine in advance of the front of the belt to force a current of air through the vines, peas, &c., as they fall from the concave to the belt, substantially as described.

In testimony that I claim the foregoing as my own I have hereto affixed my signature in 105 the presence of two witnesses.

HORIS G. FRANCIS.
